UNITED STATES PATENT OFFICE

151,625

DESIGN FOR A BRIDLE BIT

Pascal M. Kelly, El Paso, Tex.

Application May 7, 1947, Serial No. 138,864

Term of patent 7 years

(Cl. D38—2)

To all whom it may concern:

Be it known that I, Pascal M. Kelly, a citizen of the United States and a resident of El Paso, in the county of El Paso and State of Texas, have invented a new, original, and ornamental Design for a Bridle Bit, of which the following is a specification, reference being had to the accompanying drawing, forming part thereof, in which the figure is a perspective view of a bridle bit, showing my new design, the opposite side presenting substantially the same appearance as the side shown.

I claim:

The ornamental design for a bridle bit, as shown and described.

PASCAL M. KELLY.
